Patented Nov. 16, 1965

202,913

MILK BOTTLE HOLDER

Norman W. Pihan, 12 Shipley Road, Weston,
Ontario, Canada

Filed Dec. 21, 1964, Ser. No. 83,099

Claims priority, application Canada Sept. 9, 1964

Term of patent 14 years

(Cl. D44—21)

FIG. 1

FIG. 2

FIGURE 1 is a perspective view of a milk bottle holder showing my new design in tilted condition; and

FIGURE 2 is a side elevational view taken from the right side of FIGURE 1, in upright condition.

I claim:

The ornamental design for a milk bottle holder, as shown.
